(57) **CLAIM**

The ornamental design for a cooking pot, as shown and described.

DESCRIPTION

FIG. 1 shows a perspective view of a cooking pot showing my new design, according to the invention.

FIG. 2 shows a front, elevation view of the cooking pot shown in FIG. 1.

FIG. 3 shows a rear, elevation view of the cooking pot shown in FIG. 1.

FIG. 4 shows a right, elevation view of the cooking pot shown in FIG. 1.

FIG. 5 shows a left, elevation view of the cooking pot shown in FIG. 1.

FIG. 6 shows a top, plan view of the cooking pot shown in FIG. 1.

FIG. 7 shows a bottom, plan view of the cooking pot shown in FIG. 1.

The broken lines in FIGS. 1 - 5, and 7 are for the sole purpose of showing a portion of the cooking pot, and do not form a part of the claimed design.
